UNITED STATES PATENT OFFICE.

FRIEDERICH MÜLLER, OF HARTFORD, CONNECTICUT, ASSIGNOR, BY MESNE ASSIGNMENTS, TO THE AMERICAN DAN STOPPER COMPANY, A CORPORATION OF CONNECTICUT.

BOTTLE-CAPPING MACHINE.

1,159,251.

Specification of Letters Patent.

Patented Nov. 2, 1915.

Application filed November 4, 1912, Serial No. 729,283. Renewed March 27, 1915. Serial No. 17,541.

To all whom it may concern:

Be it known that I, FRIEDERICH MÜLLER, a citizen of the United States of America, residing at Hartford, in the county of Hartford and State of Connecticut, have invented new and useful Improvements in Bottle-Capping Machines, of which the following is a specification.

This invention relates to bottle capping machines and the object thereof is to so construct a machine of this class as to automatically adapt it to operate on bottles whose length may be variable without danger of breaking the bottles in the capping operation, and to this end the invention consists in the construction and arrangement of devices having these ends in view; and it further consists in various improvements pertaining to bottle capping machines, embodied in the above referred to construction and fully described in the following specification, and clearly summarized in the claims appended thereto.

In the accompanying drawings,—Figure 1 is a side elevation partly in section of the assembled machine with the parts in position for crimping the cap around the end of the bottle. Fig. 2 is a side elevation of the machine with the parts in the reverse position 30 from that shown in Fig. 1. Fig. 3 is a detail view of a part of the vertically operable head member showing the operating collar having frictional engagement therewith. Fig. 4 is a vertical sectional view of the vertically operable head-member with the parts in the same position as in Fig. 3, that is, before a bottle is inserted to be capped. Fig. 5 is a plan view of the machine. Fig. 6 is a horizontal sectional view taken on line A—B 40 of Fig. 1.

Considered as a whole the machine, in the embodiment thereof chosen for purposes of illustration consists of a frame A in which is mounted a driving shaft a , the bearings b and b^1 of which, as shown in the drawing, allow the shaft and its worm gear to be thrown into and out of operative position by means of the lever mechanism c , as follows: The worm gear a^1 fixed on shaft a 50 meshes with a driven gear a^2 on the rotatable barrel e , which is mounted on the vertical shaft d in the main frame (see Fig. 1), the shaft being continuously rotated in any well known manner.

Means are provided for locking the shaft

a with the worm gear a^1 in mesh with the gear a^2 by the provision of a stud i^1 extending through an opening in the top of the bearing b , which, when the shaft a is moved to bring the worm into mesh with its gear 60 will engage with the latch lever i pivotally supported on said bearing b , said latch being actuated by a spring i^2 . One end of this latch lever extends into the path of a cam projection e^1 on the barrel e and is tripped 65 by said projection at the end of the capping operation, and when so tripped the spiral spring c^1 which is compressed by the movement of the shaft to bring said worm gear into mesh will throw the worm out of engagement with its gear as clearly understood by referring to the drawings. To permit this movement of the shaft a , the bearing b^1 is made to swivel and the bearing b is in the form of a journal box which has a sliding movement within the frame toward and from the barrel e . Thus, to effect the rotation of the barrel and thus provide for the various movements necessary in the capping operation, the handle of the lever mechanism c (as shown in Fig. 2) is depressed and 75 at the end of the capping operation this mechanism is tripped automatically as described to stop the rotation of the barrel.

In the frame of the machine is mounted 85 the vertical sliding member 8 which, as shown in Fig. 5, is dove-tailed in the frame. This member has a stud 7 threaded into it as at 7^1 , its opposite end being provided with a roller 7^2 which extends into a cam slot e^3 90 in the barrel e ; a vertical slot 6 being provided in the frame for the movement of this stud. Said member 8 is substantially T-shaped in cross section, as shown in Fig. 1, one arm thereof extending at right angles 95 to the axis of the barrel e , and being bored out to receive the cylindrical head k which is flanged at its upper end to limit its downward movement. This head k is frictionally supported in the member 8. A preferred manner of applying said friction being shown in Fig. 3 and consisting in the application of a piece of some material 9, as leather or similar substance, between the side of said head and the arm of the member 8 in which it is supported and, by means of the screw 10 and a spring 11 interposed between said material and the screw, the degree of frictional resistance to the movement of the head k may be adjusted. With 100 105 110

the head *k* thus supported if in its downward movement it meets with any resistance which is greater than the frictional resistance above described, the head will come to 5 a stop and the member 8 sliding thereon will continue its downward movement, and this is precisely what will take place if a bottle 3 is inserted in the machine for capping and proves to be a little longer than the bottles 10 for which the machine is adjusted. Such movement of the plunger *k* relative to its support would, therefore, result in a shortened downward movement of the head *k* if means were not provided to readjust said 15 head in its support, which means are provided by screwing the flanged plug *w* into the lower end of said head *k*, which, when the member 8 moves upward will come to a bearing against the underside of the frame 20 and thus permit the member 8 to slide upward thereon to the same extent that the head *k* was displaced in said member by the contact with the longer bottle, as described. In this way the head will become automatically 25 re-adjusted to operate on bottles of the length to which it was originally adjusted.

The capping devices proper are all mounted in the head *k*. These capping devices consist of a plunger *t* having a head *p* thereon located in a cylindrical recess *o*³, bored into the lower end of the stem *o*, a spiral spring *q* being located in said recess and bearing against the head *p* to normally force the plunger downward. This plunger comes 35 to a bearing against the top of the metal cap 5 placed over the beaded end of a bottle when the head *k* moves downward and when further movement is imparted to the stem *o* in a manner to be described further.

40 The capping devices are those usually employed in crimping or constricting a relatively light metal cap over the beaded end of the bottle to close the same, these devices comprising a ring *y* of rubber or similar material which is located in the plug *w*, the opening through the head of this plug being provided with an inwardly extending flange, as shown in Fig. 1, to support said ring *y*, the end of the stem *o* and the head *p* 45 of the plunger coming down simultaneously on top of the cap and against the ring *y* serving to compress said ring and crimp the cap over the mouth of the bottle in a manner well known in this art. When the head *k* is moved downward to bring the capping devices into proper relation to the end of the bottle, as just described, it is necessary to hold the head *k* against further movement during the capping operation, and two 55 devices are shown for restraining the movement of the head during the capping operation, one of these devices being adapted to positively lock the head and the other one being adapted to apply additional frictional resistance to the head and hold it

stationary. The frictional device comprises a lever 13 (see Figs. 1 and 4) pivotally supported on the frame at 12, and having a bearing roller 14 in its upper end which comes in contact with a projection 8¹ on the member 8 as the latter moves downward. The lower end of the lever 13 which will thus be swung in toward the frame is provided with a screw 15 extending through said lever and adjusted to come to a bearing against a plug 16 in the frame which, by the movement of the lever, may be forced against the surface of the head *k* at the proper time to hold it stationary during the capping operation. The other device comprises a pair of toggle levers 17 and 18 which are operated by the arm 19 which extends upward through the frame and has an engagement with the cam slot 20 in the barrel *e*, which cam slot is so laid out that at the moment the head *k* is in its proper position at the end of its downward movement, the toggle levers will be swung upward into alinement, forcing the serrated stud 21 against the serrated surface on the side of the head, thus affording a positive lock against any further movement of the head until such time as the plug 21 shall be withdrawn by the dis-alinement of the toggle levers, the cam slot 20 being so laid out as to hold the head in locked position during the operation.

The movement of the capping devices within the head are provided as follows: The stem *o* carrying in its lower end the devices heretofore described, has a vertical movement up and down within the head *k* to effect the compression of the ring *y*, as described, which movement is imparted thereto by the shaft *n* having a screw-threaded engagement *n*¹ with said head, a pinion *r* being fixed on the upper end of the shaft *n* and the latter having a positive swiveled engagement with the upper end of the stem *o*, by means of the flanged stud *n*² entering a T-shaped slot milled across the head of the said stem. When the shaft *n* is rotated in one direction, it forces the stem *o* downward, and in the opposite direction raises the stem, thus withdrawing the capping devices inwardly relative to the lower end of the head. The rotation of the shaft *n*, therefore, must be intermittently effected in opposite directions to accomplish this end. This rotation is effected by means of a segmental gear *s*, mounted on the upper end of the device to swing in a plane at right angles to the axis of the shaft *n*, the arm *s*¹ of said gear having a stud thereon entering the cam slot *e*² in the upper end of the barrel *e*, whereby the proper intermittent movements of the shaft *n* in opposite directions are effected, the pinion *r* being made of such length as to permit the necessary vertical movements of the head *k*

and the shaft n without becoming disengaged from the segmental gear. To prevent the rotation of the head k in its support and to prevent the rotation of the stem o in the head, these two members have a spline and grooved connection, the one with the frame and the other with the head as shown in Fig. 6, o^2 representing the spline between the frame and the head and o^1 that between the stem o and the head.

By referring to Fig. 4 and comparing same with Fig. 1, it will be seen that the compressible ring y , when the stem o is drawn up into the head k , will, in its expanded state, have an opening therein large enough to receive the end of a bottle with its cap positioned thereon. From the foregoing description, it will be seen that the head k may have a vertical movement of such extent as to adapt the machine to operate on bottles whose length may vary considerably, and if the machine is adjusted to the shortest bottles, it will cap those which may be longer, without danger of breaking the same, owing to the sliding connection between the head and its support and the backing up of the plunger t with the compressible spring q . Obviously the resistance of the spring q to compression is greater than the amount of frictional resistance of the head k in its supporting member 8, the said spring being stiff enough to firmly hold the cap s in position while the depending border of the latter is constricted around the beaded end of the bottle mouth.

What I claim is:—

1. In a bottle capping machine, the combination with a bottle support, of a member to receive the upper end of the bottle to be capped, a device movable within the member to exert a pressure upon the upper end of the bottle, actuating means for said member and said device, and a device to lock said member in fixed stationary relation to the bottle during the capping operation.

2. In a bottle capping machine, the combination with a suitable fixed support for the bottle, of a movable member to permit the engagement of bottles of different lengths to be capped, actuating means for said member, and a device to lock said member in fixed stationary relation to the bottle in bottle capping position, said movable member comprising a relatively movable yieldable member to exert pressure upon the upper end of the bottle.

3. In a bottle capping machine, the combination with a suitable fixed support for the bottle to rest on while being capped, of a movable member to engage the upper end of the bottle to be capped, actuating means to cause said member to move into engagement with the upper end of the bottle, and a device to lock said member in fixed stationary relation to the bottle in such capping

position, said movable member comprising a relatively movable yieldable member movable to exert pressure upon the upper end of the bottle.

4. In a bottle capping machine, the combination, a head member to receive the upper end of the bottle to be capped, actuating means therefor, a yieldable plunger located within said member and arranged to directly engage the upper end of the bottle, and means to cause said yieldable plunger device to be moved in opposite directions, a device to lock the head member against movement during the capping operation, and means to retain said member and plunger device against rotary movement.

5. In a bottle capping machine, the combination with a reciprocable member to receive bottles of different lengths, a device to lock said member, a member having a threaded engagement with said member, and located within said reciprocable member, and means for operating said threaded member in opposite directions to exert a pressure upon the upper end of the bottle.

6. In a bottle capping machine, the combination with a bottle clamping member, a reciprocable plunger member located within the clamping member to exert a yielding pressure upon the upper end of the bottle, means for causing the bottle clamping member to exert a definite pressure during the capping operation, and means for locking the bottle clamping member comprising a clamping lever operable from the support in which the bottle clamping member is located.

7. In a bottle capping machine, the combination, a movable clamping member to receive bottles of different lengths, a yieldable plunger device located therein to engage the uppermost end of the bottle, means to operate said device and means to retain the clamping member against movement during the operation of the plunger device, comprising a cam wheel, a toggle operated therefrom and arranged to engage the movable clamping member.

8. In a bottle capping machine, the combination with a bottle engaging member adapted to engage the upper end of the bottle, and means for locking it in fixed stationary relation to the bottle during such engagement, of operative means having a yielding connection with said bottle engaging member for communicating thereto movements upon the bottle, variable in extent and adapted for positively actuating said locking member to retain the bottle engaging member in operative relation with said bottle.

9. A bottle capping machine comprising a member having reciprocating movements, actuating means therefor, a head slidably supported in said member in axial alignment

- with a bottle to be capped; bottle capping devices carried in said head, the head having an opening in the end thereof to admit the mouth of a bottle to be capped; a locking device to hold the head temporarily against endwise movement, and mechanism to actuate the capping devices against the resistance of said head while the head is held stationary by said locking device.
- 10 10. A bottle capping machine comprising a member having a reciprocating movement in a vertical plane, a head slidably supported in said member in axial alinement with a bottle to be capped, said head having an opening in the end thereof to admit the mouth of a bottle and capping devices within the head, the movement of the latter in one direction serving to position the capping devices in operative relation to the mouth of the bottle when the latter enters the opening in the end of the head, said head supporting member being slidable on the head when the movement of the head is arrested by contact of the capping devices with the bottle; together with means to actuate the head supporting member and means to actuate the capping devices at the proper time.
- 15 11. A bottle capping machine comprising a member reciprocally movable in a vertical plane, and mechanism to effect said movement, a head slidably supported in said member, and capping devices carried in said head, there being an opening in the lower end of said head to admit the mouth of a bottle; a shaft in the upper end of the head having a screw threaded engagement with the latter and adapted to operate the capping devices endwise of the head in opposite directions; a pinion on said shaft, and a

segmental gear in mesh with the pinion to rotate the latter in opposite directions, said pinion having a sliding engagement with the segmental gear during the vertical movements of the head, together with means to move said reciprocally movable head supporting member and means to actuate said segmental gear.

12. In a bottle capping machine, the combination with a bottle support; of bottle engaging means for engaging the upper end of the bottle to be capped, means yieldingly connected to said bottle engaging means for advancing it toward the bottle, and means for locking said bottle engaging means in bottle engaging position against further actuation by its yieldingly connected advancing means.

13. In a bottle capping machine, the combination with a bottle support; of bottle engaging means for engaging the upper end of the bottle to be capped, means yieldingly connected to said bottle engaging means for advancing it toward the bottle, and means for locking said bottle engaging means in fixed stationary relation to the bottle, in bottle engaging position.

14. In a bottle capping machine, the combination with a bottle support; of a bottle clamping member for holding the upper end of the bottle actuating means having frictional engagement with said clamping member for moving the same toward and away from the bottle and means for locking the clamping member, against movement, in bottle clamping position.

FRIEDERICH MÜLLER.
